No. 889,193.

PATENTED JUNE 2, 1908.

G. C. BOURDEREAUX.
GAS EXPLOSION ENGINE.
APPLICATION FILED OCT. 15, 1906.

UNITED STATES PATENT OFFICE.

GEORGE C. BOURDEREAUX, OF PEORIA, ILLINOIS, ASSIGNOR OF ONE-THIRD TO MELVIN W. SWARTZ AND TWO-THIRDS TO JULIA BOURDEREAUX, OF PEORIA, ILLINOIS.

GAS-EXPLOSION ENGINE.

No. 889,193.

Specification of Letters Patent.

Patented June 2, 1908.

Application filed October 15, 1906. Serial No. 338,975.

To all whom it may concern:

Be it known that I, GEORGE C. BOURDEREAUX, citizen of the United States, residing at Peoria, in the county of Peoria and State 5 of Illinois, have invented certain new and useful Improvements in Gas-Explosion Engines; and I do hereby declare that the following is a full, clear, and exact description of the invention, which will enable others 10 skilled in the art to which it appertains to make and use the same.

This invention has reference to improvements in gas and gasolene engines.

The invention relates more particularly to 15 the valve motion in such engines.

The object of the invention, primarily, is to provide a gas explosion engine that will instantly open to its fullest extent both the gas intake valve and the exhaust valve and close 20 them slowly.

Another object is to provide means for accomplishing these movements.

A further object of my invention is to fully 25 open the exhaust valve instantly in order that the burned and super heated gases may be instantly ejected so the heat therefrom will not be absorbed by the metal.

A further object is to instantly open the 30 gas intake valve to its fullest extent whereby the gas can be entered to the cylinder with as little loss of power as possible.

In order to make the above object more 35 clearly understood it may be stated that in engines of this type the opening of the valves is usually very slow. The opening movement of the exhaust valve is so slow in fact that the highly heated gases after being exploded cannot be quickly liberated and the heat therefrom is communicated to and absorbed by the cylinder until that member becomes red hot and from this condition many 40 troubles arise as is well known.

In air cooled engines when used on horseless vehicles it often becomes necessary to 45 stop so as to permit the cylinder to cool. In water cooled engines this trouble does not so often occur but the water systems are expensive and troublesome in many ways. The air cooled engine is to be preferred if undue 50 heating and the troubles arising therefrom can be overcome. It is a fact also with regard to the intake valve that its movement is usually so little and so slow that power is taken from the engine for drawing in the 55 gases whereas if the valve were given a quick

and full movement there would be no appreciable loss of power and consequently the engine would have greater efficiency.

In studying the difficulties encountered I have found that the burned gases must be 60 disposed of as quickly as possible before the metal parts absorb the heat, and if the valve is instantly opened to its fullest extent the gases are permitted to escape at once assisted by the piston and by having the valve opened 65 in this manner, also, there can be no compression of the burned gases and no appreciable power is required from the engine to complete the expulsion.

In the appended drawings, Figure 1 is a 70 sectional elevation of the engine viewed from one side. Fig. 2 is a rear elevation of the engine showing part of the base removed to show my improvements. Fig. 3 is a detail view of my valve operating means. Fig. 4 is 75 a like view shown in a slightly advanced position from that shown in Fig. 3. Fig. 5 is a view of the same in a still further advanced position. Fig. 6 is another view and Fig. 7 still another view thereof. Fig. 8 is an elevation of the valve for the intake or discharge of gases showing part of the cylinder.

The cylinder is represented by the letter A, and B is a base on which it is mounted.

C is the piston, common to engines of this 85 type, having the piston-rod D connected therewith, said rod having the usual connection with the crank-shaft E.

F and G indicate the gas intake and exhaust pipes respectively within each of 90 which is a valve stem, that for the exhaust being indicated in Fig. 1 by the letter H and that for the gas intake by the letter J in Fig. 8. Each stem has a flared disk L, one of which is shown in Fig. 8, to seat in a conical 95 opening in the head of the cylinder thus constituting a valve. At the top of the stem is an enlargement beneath which is a spiral spring M which bears upon the pipe as shown, said spring tending to hold the valve closed. 100 At two places are erected posts N each having pivoted thereon a lever O one end of which bears upon the stem of its respective valve and the other end having attached thereto a valve-rod P. The lower end of 105 each of the latter has a rounded head as at Q. Parallel to the crank-shaft E is a cam-shaft R receiving motion from the said crank-shaft E through the gear wheels S and T shown in dotted lines in Fig. 1, the gear S being shown 110

Fig. 2 and carried by the cam-shaft, while the gear T is carried by the crank-shaft. Upon the shaft R are secured two cam members U and V the former for operating the intake valve beneath whose rod P it rotates, the latter cam V operating the exhaust valve.

A peculiarity of the levers O described above, is that in place of being pivoted at a point midway between their ends to the posts N as in other engines, they are pivoted so as to have a short and a long end as shown, the valve-rods P having connection with the short ends while the long ends are employed to depress the valves. Another peculiarity is in the form of the cams U V described. It will be noted in the detailed views that each cam is provided with a straight edge a which is tangential to the periphery of the hub thereof, while its intermediate end is curved and then slants toward the periphery of the hub at the opposite side at an angle to the said straight portion a. A still further peculiarity is that unlike other cam operated valve rods, my valve-rods instead of being positioned directly over the center of the axis of revolution of the cam are placed at one side thereof or toward the end of the cam as positioned in Figs. 1 and 3. The cams are set at right angles to one another or as familiarly known as "on the quarter", this being the position necessary to operate the valves in their proper order and at the proper time.

As viewed in Fig. 1 the piston is in the act of descending, the crank having just passed "over center." At the moment of passing the center the cam U arrives beneath and engages the valve-rod of the gas intake valve.

In Figs. 3 to 7 the action of the cams and the valve-rods is illustrated. When the valves are closed the valve-rods are in their lowest position, their heads Q resting upon the hubs of their respective cams. When the cam U meets its rod the latter is instantly raised to its full height as in Fig. 4. Just here it is to be understood that if the valve-rod were placed immediately over the center of the shaft, or the center of revolution of the cam, the straight edge a of the latter would gradually push the rod upward, if, indeed, it would be raised at all, by reason of the side pressure thereupon instead of a direct lift; consequently a curved surface, rather than a straight one, would have to be employed to raise it and if curved so as to obtain the desired raising action the movement would necessarily be a slow one. But in my form, by having the straight surface a, described, with the rod resting thereupon as shown, the revolution of the cam must instantly raise the rod to its full height. Now, since the rod is pivoted to the short end of the rock-arm, or lever, O the long end of the latter will be instantly depressed to depress the valve and open it to its widest extent at once said

lever thus multiplying the movement in the valve-rod to produce the desired quick result. As the cam continues to move the rounded end is carried beneath the valve-rod and the latter in following said rounded end travels slowly down to its lowest position. By thus constructing the cam the raising movement of the rod must be fast while the lowering movement thereof is necessarily slow. By this means the valve is opened to its fullest extent at the proper moment for exhaust and is held open a sufficient length of time during the descent of the valve-rod upon the curved cam, to permit full discharge of the gases. The same is true of the intake valve which is opened instantly to permit the piston to draw in the full charge of gases and closes slowly so that by the time the piston has reached its lowest position and has taken in the bulk of gases the valve is ready to close.

In this type of engine and known as the "four-cycle", the piston having drawn in its full charge of gases returns and compresses it at which time the gas is fired by the means usually employed thereby driving the piston to exert force upon the crank-shaft. The exhaust valve is then opened and the burned gases ejected, the piston then once more drawing in a new charge of gas. As I have already stated, it becomes necessary, at times, where the so-called air cooled engine is employed in horseless vehicles, to stop on the road to allow the cylinder to cool, but in my engine the burned gases are liberated so suddenly and completely that excessive heating never takes place the engine running for hours in a stationary position without undue heating.

It is not my intention to confine myself to the exact arrangement shown since it may be varied to adapt it to different types of engines while retaining the desired relation of the various parts, and it can be readily attached to engines already built so as to render them of greater value.

An engine that produces a given horse power under the old conditions, when provided with my valve mechanism, can develop a third more power from the fact that the valves are opened to their widest extent instantly so that the power is not wasted to any appreciable extent in drawing in or expelling the gases.

Having fully set forth the construction of my improved invention and the advantages to be derived therefrom, I claim:

1. In a gas explosion engine, its valves for the reception and exhaust of gases, adapted to open suddenly to their fullest extent, and also adapted for closing at a slower speed than that at which they are opened for the purposes described, and mechanism in connection therewith for causing such action.

2. In a gas explosion engine, an inlet valve

and an exhaust valve, and mechanism in connection therewith for opening them and for causing them to close at a speed slower than that at which they are opened.

5. 3. In a gas explosion engine, an inlet valve and an exhaust valve, and timed mechanism for imparting a sudden full opening to the valves, and for causing them to be closed slower than they are opened for the purposes 10 described.

4. In a gas engine, a valve, a cam, a valve-rod for at one end operating said valve, and bearing at its other end directly upon the cam, said cam having provision for suddenly 15 shifting the valve-rod to open the valve with a quick motion, and having provision also for causing the valve to close with a movement slower than that at which it is opened.

5. In a gas engine an inlet valve and an 20 exhaust valve, a cam for each valve, valve operating means between each cam and its valve, each cam adapted for quickly opening its respective valve through the operating means, and adapted also to cause the valve 25 to close more slowly than it opens.

6. In a gas engine an inlet valve and an exhaust valve, a cam for each valve, a valve-rod for each cam each bearing directly upon its cam, and adapted for operating the valves, 30 the cams having provision on one side for quickly opening the valves through the valve rods, and having provision on their opposite sides for causing the valves to close more slowly than it opens.

35 7. In a gas engine, a valve, a cam, a valve-rod for operating the valve the same bearing directly upon the cam at one side of the axis of the latter, said cam having a flat surface at one side for instantly operating the valve-rod 40 to open the valve, and having a curved surface at the other side for causing slow movement of the valve-rod and consequent slow closing of said valve.

8. In a gas engine, a valve, a cam, a valve-45 rod bearing directly upon the cam at one side of its axis, the cam having provision for quickly operating the valve-rod to suddenly open the valve, and having provision also for permitting slow movement of the valve-rod in the opposite direction and thereby causing slow closing of the valve, and means 50 between the valve stem and the valve for multiplying the movement of the valve stem for producing longer movement in the valve 55 than that of the valve-rod.

9. In a gas engine, a valve, a cam, a valve-

stem bearing directly upon the latter, said cam having provision for moving the rod quickly in one direction and causing its slow movement in the other direction, and a rocking member operated by the valve-rod to contact with the valve and to operate the same, said member having a short and a long extension, the valve-rod acting upon the former, the latter acting upon the valve for 60 the purposes set forth.

10. In a gas explosion engine, a valve, a pivoted lever having a short arm and a long valve-operating arm, a valve rod engaging the short arm, a rotating cam shaft at one 70 side of the axial line of said rod, and a cam fixed to said shaft and adapted to suddenly slide the rod longitudinally and permit its return after a predetermined interval.

11. In a gas explosion engine, an inlet 75 valve, an exhaust valve, pivoted levers each having a short arm and a longer valve actuating arm, valve rods connected to the shorter arms, respectively, an engine driven shaft at some distance from the axial lines of 80 said rods, and cams fixed to said shaft and each adapted to slide one of said rods longitudinally and approximately instantaneously and permit it to return to initial position after a predetermined interval.

85 12. A gas explosion engine having a gas inlet valve and an exhaust valve, a lever for operating each, a valve-rod for each lever, a cam-shaft driven by the engine shaft, and a cam carried on the shaft adjacent to each of 90 the said valve-rod, said cams adapted to suddenly raise the valve-rod, and also adapted to permit them to slowly return to their position of rest for the purposes described.

95 13. A gas explosion engine having a gas inlet valve and an exhaust valve, a lever for depressing each valve, said lever being fulcrumed to have a short and a long end, the long end adapted for depressing the valve, a 100 revolving shaft, a pair of cams secured thereon, each having a straight face at one side and a rounded face at its opposite side for the purposes set forth, and valve operating means between the cams and the levers.

105 In testimony whereof I affix my signature, in presence of two witnesses.
